TOOL FOR REMOVING CONNECTORS
FROM TREADS

Welton L. Crosby, Phoenix, Ariz.

Application September 21, 1944, Serial No. 555,161

9 Claims. (Cl. 59—7)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to tools and more particularly to a tool for removing connectors from the treads of track laying vehicles.

An object of the present invention is to provide a tool adapted to remove connectors from tank treads in order that the treads may be either repaired, reversed, or replaced.

It is a further object of the invention to provide a tool of the type mentioned above wherein the upper part of the connector is supported while removing the connector from the tread so that the removal thereof is facilitated.

Track-laying vehicles have a pair of endless tracks composed of connected blocks or treads. Each tread has embedded therein a pair of pins extending beyond opposite sides of the tread. Adjacent treads are pivotally connected by connectors mounted upon the extending portions of the tread pins. It is frequently necessary to remove some or all of the treads for replacement or repair purposes. In addition, the conventional type of tread can be reversed when one side has worn down from contact with the ground so that the opposite and unused side of the tread is positioned on the outside of the track. The connectors connecting adjacent treads have upstanding ears extending inwardly of the track and engageable with the sprockets for driving the track. The removal of these connectors from the pins embedded in the treads is an extremely difficult operation with ordinary tools since it is impossible to apply an axial force or blow to the connector. Striking the extending ear of the connector with a hammer or similar instrument is the conventional method for removing the connectors. This, however, results in bending the connectors and causing them to bind on the pins, thus consuming a large amount of labor and time and frequently damaging the connectors so that they cannot be used again.

The tool embodied in the present invention eliminates the above mentioned disadvantages of the conventional practice and facilitates the removal of the connectors. This is accomplished by providing a punch having an extending arm terminating in a hook shaped end, the latter being adapted to engage the upper part of the connector and to thereby support the latter while driving the connector from the tread pins. This arm may be either rigidly mounted upon the punch, or may be resiliently connected thereto by

2

means of a spring, and functions to hold back the top of the connector thus preventing the latter from binding on the tread pins during its removal therefrom.

Other objects of the invention will be made more apparent as this description proceeds, particularly when considered in connection with the accompanying drawings in which:

Figure 1 is a plan view of a tool embodying the present invention in position for removing a connector from a pair of adjacent treads;

Figure 2 is a front elevation of the construction shown in Figure 1;

Figure 3 is a plan view of a modified form of a tool;

Figure 4 is a front elevation, partly in section, of the modification shown in Figure 3, and

Figure 5 is a front elevation of another modification.

Referring now to the drawings, it will be noted that Figures 1 and 2 illustrate an embodiment of the present invention. In detail, 1 and 2 are adjacent treads of the track of a track-laying vehicle. Embedded in each track and extending a short distance beyond each side thereof are a pair of pins 3. The treads 1 and 2 are pivotally connected together by connectors 4, each of which is provided with a pair of apertures 5 adjacent the bottom thereof and adapted to engage the extending portions of the pins 3. Extending upwardly from each connector is an arcuate ear 6 which is adapted to engage the drive sprockets to drive the track as well as to guide the latter. These connectors are assembled to the treads of the track by driving them upon the pins 3. Once assembled, however, it is difficult to remove the connectors without damaging either the connectors or the pins since it is impossible to apply force upon the connector in a direction axially of the pins. The treads prevent any force from being applied to the connector except at points laterally spaced from the apertures 5. In addition, the upstanding ears 6 of the connectors on the opposite side of the treads likewise hinder the application of force in an axial direction. It

will be noted that if a force such as a blow from a hammer is applied to an ear 6 of a connector, there is a resulting tendency of the connector to bind upon the pins 3, and either the connector or the pins may be damaged.

7 is a punch having a driving end 8 and a driven end 9 and constructed of any suitable metal such as hardened steel. The punch is shown as being tapered from a larger diameter at the driven end 9 to a smaller diameter at the driv-

ing end 8. Intermediate the ends of the punch is a handle 10 extending at right angles thereof. Near the driving end of the punch is an arm 11 which extends from the body of the punch at an acute angle toward the driving end of the latter. This arm is also made of steel and may be integral with the punch or it may be welded or otherwise suitably secured thereto. The arm 11 terminates in a hook shaped end 12 which is adapted to hook over the upper portion of the ear 6 of the connector 4. The length of the arm 11 and the driving end 8 of the punch are so proportioned that when the driving end of the punch is positioned against the inner surface of the connector adjacent the top of the tread, the hook 12 will engage with the top of the connector 4. It will be noted that in this position the punch 9 is positioned at an angle with the pin 3 in order to provide clearance between the punch and the top of the connector 4 on the opposite side of the track.

In the position described above and illustrated in Figure 2, it will be noted that when force is applied to the driven end 8 of the punch by a hammer or other suitable means, that force is transmitted through the body of the punch and is applied against the connector in an outwardly direction as near as possible to the axes of the pins 3. At the same time the hook 12 upon the arm 11 is in engagement with the top of the ear 6 of the connector and functions to hold back the latter, thus preventing the connector from bending and also from binding upon the pins 3. In this manner, the connectors can be readily removed from the treads in a relatively short time and with the minimum of effort and also without damaging the connector or the tread pins. This permits the treads of a track-laying vehicle to be replaced or reversed in a much shorter time than has heretofore been possible and inasmuch as there are a great number of treads and connectors in each track, it will be apparent that the saving of time is large.

Referring now to Figures 3 and 4, it will be noted that I have illustrated a modified tool in which 13 is a punch provided with an integral collar or shoulder 14 intermediate its ends. Encircling the body of the punch 13 and also the collar 14 is a housing 15. The housing 15 is adapted to be movable axially of the punch and is provided with a bore 16 in which is received a spring 17 encircling the punch 13. The forward end of the body 15 has an inturned flange 18 adapted to form a stop for the shoulder 14 on the punch and the opposite end of the body is provided with a cap 19 threaded therein and cooperating with the collar 14 to retain the spring 17.

Extending from the upper portion of the body 15 is an arm 20 terminating in a hook shaped end 21 adapted to engage the upper portion of the connector ear 6. The arm 20 is welded or otherwise suitably secured to the body 15. It will be noted that in this form of the invention, the arm 20 is resiliently connected to the punch 13 through the medium of the spring 17 and when the parts of the tool are in the position shown in Figure 4, the spring 17 is under compression and tends to force the body 15 and the arm 20 toward the driven end of the punch 13. This results in holding the hook shaped end firmly against the top of the connector; and when the punch is driven against the connector the action of the spring and the inertia of the arm function to hold back the top of the connector and to

prevent the latter from binding on the pins 3 while the connector is being removed. An additional advantage of this construction resides in the fact that the relative movement between the arm 20 and the punch 13 permits the use of the tool with various types and sizes of connectors.

The construction shown in Figures 3 and 4 also includes means for guiding the punch with respect to the connectors. This means comprises a pair of guide rods 22 secured to opposite sides of the body 15 and extending forwardly therefrom a distance sufficient to embrace the opposite sides of the connector 4. In this manner the driving end of the punch is automatically centered with respect to the connector 4 and is prevented from moving laterally with respect thereto during removal of the connector. The rearward end of the punch 13 is also guided by means of a support 23 depending from the lower part of the body 15 at the rearward end thereof. This support is shown as being integral with the body 15 but may be made separate if desired. The forward edge of the support 23 is arcuate in shape and is inclosed by a sheet metal strip 24 which has a pair of rearwardly extending legs 25 and 26, the latter being adapted to embrace the connector 4 at the side of the tread opposite the connector being removed. With this construction the legs 25 and 26 guide the tool with respect to the rear connector, and if this connector has already been removed, the support 23 serves as a means for resting the tool upon the tread.

The modification shown in Figure 5 is similar to the construction of Figures 3 and 4 in that the arm 27 is resiliently mounted with respect to the punch 28. This construction includes the bracket 29 secured to the upper side of the punch 28 intermediate the ends of the latter. The bracket 29 is provided with an aperture 30 through which extends the rearward end 31 of the arm 27. The end 31 of the arm 27 is reduced in diameter and forms a shoulder 33 with the body of the arm. A spring 32 is positioned between the bracket 29 and the shoulder 33 formed on the arm and a second spring 34 is positioned between the opposite side of the bracket 29 and the washer 35, the latter being held in place by a nut 36 threaded on the end 31. With this construction, it will be noted that movement of the arm 27 in either direction relative to the punch 28 is resisted by spring compression which may be varied by adjusting the nut 36. The forward end of the arm 27 is provided with a hook shaped portion 27 engageable with the upper part of the connector and it will be apparent that when the connector is removed by applying a blow upon the driven end of the punch 28, the arm 27 will operate through its resilient mounting in the bracket 29 to retard and hold back the upper part of the connector, thereby preventing it from cocking or binding during the removal of the connector from the tread.

Although I have shown specific modifications of my invention, it will be understood that various changes are contemplated. For example, the punch may be provided with a relatively wide driven end having an elongated opening adapted to embrace the upwardly extending portion of the connector opposite the one being removed. This enables the punch to be operated in a position substantially parallel to the pin.

Accordingly, the invention should not be limited except as expressed in the appended claims. What I claim is:

1. A device for removing connectors from the treads of track-laying vehicles comprising an elongated punch having a driving end and a driven end, and an extension positioned at the driving end of said punch and terminating in a hook shaped end, said hook shaped end being laterally spaced from said driving end a predetermined distance and restrained against movement laterally away from said punch during operation of the device.

2. A device for removing connectors from the treads of track-laying vehicles comprising an elongated punch having a driving end adapted to engage the connector intermediate its ends and a driven end, and an arm extending laterally from said punch and terminating in a hook shaped end laterally spaced from the driving end of said punch and adapted to engage one end of a connector to support the latter while removing the connector, said arm being mounted for sliding movement relative to said punch.

3. A device for removing connectors from the treads of track-laying vehicles comprising an elongated punch having a driving end and a driven end, and an extension slidably mounted on said punch and having a hook shaped portion laterally spaced from said driving end, and a spring arranged to resist the sliding movement of said extension relative to said punch.

4. A device for removing connectors from the treads of track-laying vehicles comprising an elongated punch having a driving end adapted to engage the connector intermediate its ends and a driven end, a member carried by said punch and movable longitudinally thereof, said member having an extension positioned adjacent the driving end of the punch and terminating in a hook shaped end laterally spaced from said driving end and adapted to engage one end of a connector to support the latter, and a spring urging said member toward the driven end of said punch.

5. A device for removing connectors from the treads of track-laying vehicles comprising an elongated punch having a driving end adapted to engage the connector intermediate its ends and a driven end, a member carried by said punch and movable longitudinally thereof, said member having an extension positioned adjacent the driving end of the punch and terminating in a hook shaped end laterally spaced from said driving end and adapted to engage one end of a connector to support the latter, a spring urging said member toward the driven end of said punch, and a stop on said punch for limiting the movement of said member toward the driven end of the punch.

6. A device for removing connectors from the treads of track-laying vehicles comprising an elongated punch having a driving end adapted to engage the connector intermediate its ends and a driven end, a member encircling said punch intermediate its ends and movable longitudinally relative thereto, an arm extending from said member at an acute angle to the axis of the punch, a hook shaped portion at the end of said arm adapted to engage one end of a connector, and a coil spring positioned within said member and encircling the punch, said spring having one end engageable with said punch and the op-

posite end engageable with said member whereby said member is urged toward the driven end of the punch.

7. A device for removing connectors from the treads of track-laying vehicles comprising an elongated punch having a driving end adapted to engage the connector intermediate its ends and a driven end, a member encircling said punch intermediate its ends and movable longitudinally relative thereto, an arm extending from said member at an acute angle to the axis of the punch, a hook shaped portion at the end of said arm adapted to engage one end of a connector, a coil spring positioned within said member and encircling the punch, said spring having one end engageable with said punch and the opposite end engageable with said member whereby said member is urged toward the driven end of the punch, and a support depending from said member and engageable with the tread to support said punch at an acute angle with the plane of the tread.

8. A device for removing connectors from the treads of track-laying vehicles comprising an elongated punch having a driving end adapted to engage the connector intermediate its ends and a driven end, a member encircling said punch intermediate its ends and movable longitudinally relative thereto, an arm extending from said member at an acute angle to the axis of the punch, a hook shaped portion at the end of said arm adapted to engage one end of a connector, a coil spring positioned within said member and encircling the punch, said spring having one end engageable with said punch and the opposite end engageable with said member whereby said member is urged toward the driven end of the punch, and a pair of guide members extending from said member toward the driving end of said punch and adapted to embrace a connector to guide the punch.

9. A device for removing connectors from the treads of track-laying vehicles comprising an elongated punch having a driving end adapted to engage the connector intermediate its ends and a driven end, a bracket extending laterally from said punch intermediate its ends, said bracket having an aperture therethrough, a rod having one end reduced in diameter and extending through the aperture, said rod having a hook shaped portion at its opposite end adapted to engage one end of a connector to support the latter, and a pair of coil springs embracing the reduced end of said rod on opposite sides of said bracket.
